US0D1035586S

(12) **United States Design Patent** (10) **Patent No.:** **US D1,035,586 S**
(45) **Date of Patent:** ** *Jul. 16, 2024

(54) **POWER ADAPTER**

(71) Applicant: **Dongguan Wontravel Electric co., Ltd.**, Dongguan (CN)

(72) Inventor: **Liangguan Lin**, Shenzhen (CN)

(*) Notice: This patent is subject to a terminal disclaimer.

(**) Term: **15 Years**

(21) Appl. No.: **29/865,900**

(22) Filed: **Aug. 18, 2022**

(51) LOC (14) Cl. **13-03**

(52) U.S. Cl.

USPC **D13/137.2**

(57) **CLAIM**

The ornamental design for a power adapter, as shown and described.

DESCRIPTION

FIG. 1 is a front elevation view of a power adapter showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof; and,

FIG. 7 is a perspective view thereof.

1 Claim, 7 Drawing Sheets
